INVENTOR
Thomas L. Ryan

UNITED STATES PATENT OFFICE.

THOMAS L. RYAN, OF MUNCIE, INDIANA.

DESIGN FOR A PORTABLE LAMP BASE.

61,331.

Specification for Design.

Patented Aug. 1, 1922.

Application filed July 25, 1921. Serial No. 487,545. Term of patent 3½ years.

To all whom it may concern:

Be it known that I, THOMAS L. RYAN, a citizen of the United States, residing at Muncie, in the county of Delaware and State of Indiana, have invented a new, original, and ornamental Design for a Portable Lamp Base, of which the following is a specification, reference being had to the accompanying drawing, forming a part thereof.

Figure 1 is a side view, and Figure 2 is a top plan view of a portable lamp base, showing my new design.

I claim:

The ornamental design for a portable lamp base, as shown.

THOMAS L. RYAN.
